UNITED STATES PATENT OFFICE.

ORRA E. BYRON, OF SAN FRANCISCO, CALIFORNIA.

CARBURETER.

No. 890,494.

Specification of Letters Patent.

Patented June 9, 1908.

Application filed August 13, 1907. Serial No. 388,301.

To all whom it may concern:

Be it known that I, ORRA E. BYRON, a citizen of the United States, and a resident of San Francisco, in the county of San Francisco and State of California, have invented a new and Improved Carbureter, of which the following is a full, clear, and exact description.

My invention relates to carbureters, my 10 more particular object being to maintain an even vacuum under all working conditions. To this end I so construct the carbureter as to admit varying quantities of air to the mixing chamber, the admission being controlled 15 ultimately by the condition of the vacuum within the mixing chamber.

Reference is to be had to the accompanying drawings forming a part of this specification, in which similar characters of reference 20 indicate corresponding parts in all the figures.

Figure 1 is a central vertical section through my improved carbureter, showing the relative positions of the various valvular members for regulating the air supply, and 25 further showing the position of the spraying nozzle and of the heating jacket for the gases traveling from the carbureter to the engine; Fig. 2 is a central section somewhat similar to Fig. 1, but taken upon the line 2—2 of 30 Figs. 1 and 3, looking in the direction of the arrows and showing a float-controlled needle valve for regulating the supply of hydrocarbon to the carbureter; and Fig. 3 is a horizontal section upon the line 3—3 of Fig. 1 35 looking in the direction of the arrows and showing the relative arrangement of the valvular members.

A hollow body portion 1, is provided with a reduced portion 1^a, and is tapped by an 40 inlet pipe 2 and an outlet pipe 3, the latter leading to the engine. Cylinders 4, 5, of different diameters, are connected integrally together and are disposed concentrically. The cylinder 4 is connected with the reduced 45 portion 1^a by ribs 1^b. These cylinders are provided respectively with a port 6 and two ports 7, all having the form of arcuate slots. A partition 8, of annular conformity, encircles the cylinder 5 and is set off therefrom so 50 as to form an annular compartment 9, encircling said cylinder.

Slidably mounted within the cylinder 5 is a smaller cylinder 10, provided with a substantially annular portion 11 connected integrally therewith and spaced therefrom by arcuate slots 12. These slots constitute

ports and are adapted to register with the ports 7 and are of greater depth than the latter. A spraying nozzle 13 is provided with a needle valve 14 operated by hand. This 30 needle valve regulates the flow of liquid hydrocarbon through a passage 15 and is used for vaporizing said hydrocarbon as the latter is discharged upwardly into the cylinder 10.

A disk 16 is provided with an upturned flange 17 of annular conformity, integral therewith and slidably engaging the inner surface of the cylinder 4. The disk 16 is also provided with openings 16^a. The disk 16 with its flange 17 and cylinder 10 having its 70 annular portion 11, together constitute a valvular member. This valvular member as a whole is movable relatively to the cylinders 4, 5. The proportions of the parts are such that when the valvular member is lowered, 75 the annular portion 11 gradually uncovers the ports 7 and when these are completely open, the flange 17 begins gradually to uncover the port 6.

A valve stem is shown at 18 and is connected with a diaphragm 19 mounted within a diaphragm chamber 20. The valve stem 18 terminates in an adjustable head 21 which is engaged constantly by a spiral spring 22 encircling the valve stem. The normal position of the diaphragm 19, when the device is 80 idle, is the one shown. When, however, there is a partial vacuum below the diaphragm 19, the valve member descends to a greater or lesser extent dependent upon the 85 pull exerted by the vacuum.

A jacket 23 of annular form encircles the outlet pipe 3 and is provided with radially disposed tubes 24. These tap into pockets 25 provided in the outlet pipe 3. Exhaust 95 gases of combustion are supplied into the jacket 23 by a pipe 26, whence they pass into the pockets 25 and outwardly through a pipe 27, thus making their escape. In doing this they heat the air and vapor passing through 100 the outlet pipe 3.

The body portion 1 is provided with an extension 28 in which is a cylindrical weight 29. Below the extension 28 and integral therewith is a threaded boss 30 having an aperture 105 31 disposed centrally thereof. This boss is engaged by a threaded pipe 32 through which the hydrocarbon liquid is supplied to the carbureter. A guide 33 is disposed over the aperture 31 and extending through this guide 110 34 is a needle valve extending entirely through the weight 29, the upper end of this needle

valve being shown at 35 and projecting through the upper surface of the body portion 1.

5 Mounted upon a pivot 36 is a lever 37 having an upwardly projecting end 37^a. A float 38, having substantially the form of a hollow ring, encircles the smaller cylinder 10 and rests upon a volume of hydrocarbon liquid 40 contained in the body portion 1.

10 Whenever the body portion is nearly empty, the ring float 38 being no longer buoyed up rests partially upon the end 37^a of the lever 37, thereby turning the lever and raising the weight 29. The needle valve 34 is therefore lifted from its seat and the liquid 15 flows in. This lifts the ring float, allowing the lever 37 to rise, and the weight 29 causes the needle valve 34 to again close the aperture 31. In this way the inflow of gasoline 20 is so regulated that the supply within the carburetor is approximately constant.

The operation of my device is as follows: The inlet pipe 2 communicating with the air, and the outlet pipe 3 being connected with 25 the engine, and the latter being in action, a partial vacuum is produced below the diaphragm 19. This causes the diaphragm to descend and the annular member 11 partially uncovers the ports 7. The needle valve 14 30 being opened by hand to a proper degree and the suction being continued, the fuel hydrocarbon is sprayed from the nozzle 13 and vaporized, the vaporization being improved by the liquid striking against the under side of 35 the disk 16 which thus serves as a baffle. The admixture of air and vapor constitutes the explosive aeriform body employed for driving the engine. The explosive mixture next passes out through the outlet pipe 3 and in 40 so doing is heated, as above described.

The ports 7 are the ones ordinarily used, and hence I designate them as the main ports. When, however, the tension of the vacuum exceeds a certain predetermined limit, and 45 the diaphragm 19 is depressed accordingly so that the ports thus become partially or entirely uncovered, the supply of air is greatly increased for the reason that air is now ad-

mitted through the ports 6 and 7. I therefore designate the ports 6 as auxiliary ports. 50

Owing to the excessive admission of air, the excessive vacuum is reduced. Hence, the carburetor is self-regulating and tends to keep the vacuum uniform in the outlet pipe 3.

Having thus described my invention, I 55 claim as new and desire to secure by Letters Patent:

1. In a carburetor, the combination of a member provided with ports through which air can pass, and a valve member provided 60 with portions for successively uncovering said ports so as to permit the passage therethrough of varying quantities of air, and a vacuum-controlled diaphragm connected with said valve member for actuating the 65 same.

2. In a carburetor, the combination of a large cylinder provided with a port, a small cylinder provided with a port, a valve member provided with a flange slidably mounted 70 within said large cylinder and further provided with a portion slidably mounted within said small cylinder, said flange and said small portion of said valve member being adapted to uncover said ports in a predetermined order of succession, and vacuum-controlled mechanism for moving said valve member. 75

3. In a carburetor, the combination of a body portion provided with a main port and 80 with an auxiliary port, and a valve member provided with a portion normally covering said main port, and with another portion normally covering said auxiliary port, said portions of said valve member being so positioned as to uncover in succession said main port and said auxiliary port, and vacuum-controlled mechanism connected with said valve member for moving the same. 85

In testimony whereof I have signed my 90 name to this specification in the presence of two subscribing witnesses.

ORRA E. BYRON.
